UNITED STATES PATENT OFFICE

2,617,988

SUSPENSION LACING FOR PROTECTIVE HELMETS

Anthony L. Alesi, Philadelphia, Pa.

Application April 7, 1950, Serial No. 154,701

24 Claims. (Cl. 2—3)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

Since the invention of the first helmet, means have been provided to space the outer protective shell thereof from the head of the wearer whereby to prevent transmission of the shocks received by the shell. A well known form of such means is to support the shell from a helmet suspension which may comprise a cradle resting atop the wearer's head and a sweat band encircling the head. The sweatband and the top of the cradle are spaced from the shell by a variety of spacing means.

Commonly, the sweatband is spaced from the shell in any suitable manner and the lower edges of the cradle are secured directly to the shell. Examples of this structure are seen in the patents to Scholl et al., No. 2,371,712 of March 20, 1945; Riddell, No. 2,250,275, dated July 22, 1941; and Riddell, No. 2,359,387, dated October 3, 1944. Moreover, in all of these patents the sweatband is spaced from the shell by securing spaced points of a taut flexible member to the interior of the shell to provide an endless series of chords about the interior of the shell and thereafter securing spaced points of the sweatband to the medial points of the chords. The lower edges of the cradles are anchored directly to the shell.

This structure provides considerable resiliency in the sweatband but imparts none whatever to the cradle. Moreover, by merely anchoring spaced points of the flexible member to the shell, no protection is provided at the anchored points of the flexible member except by stretching the sweatband thereacross. Thus, there is danger of providing too much resiliency in the support whereby a heavy blow in the region of one such anchor point may result in contact of the helmet shell at such point with the head. Riddell recognized this weakness and has sought to correct it in Patent No. 2,359,387, supra, wherein a second flexible member has been secured to the first flexible member and in turn supports the sweatband. However, this structure doubles the cost of the sweatband support and also requires the overall diameter of the shell to be increased. Moreover, the prior art spaces the sweatband from the shell and connects the lower edges of the cradle to the shell, thus, only the top of the cradle is in contact with the head whereby a relatively unstable support is provided which provides but little resistance to accidental tilting of the helmet on the head.

The device according to the invention elimi-

2

nates both objections, first, by supporting the cradle from the flexible member rather than from the shell. This permits the cradle to embrace the head closely in full cooperation with the sweatband. Secondly, by so connecting the flexible member to the shell that the ends of each chord overlap the adjacent ends of each adjacent chord I am able to achieve the effect of the last mentioned Riddell patent without incurring the objectionable features thereof.

With the foregoing in view, it is an object of my invention to provide an improved helmet suspension.

15 A further object is to provide an improved chordal-type sweatband support for a helmet.

A further object is to provide an improved means for anchoring a cradle of the type described to a helmet.

20 A further object is to provide in a helmet improved combined means for anchoring a cradle and supporting a sweatband.

A further object is to provide an improved means for anchoring a cradle to a helmet which permits the cradle to be anchored in a plurality of different ways, each providing different degrees of resiliency and/or the simultaneous use of two or more of such ways whereby selected parts of the cradle may be anchored so as to have different degrees of resiliency.

25 30 A further object is to provide a single chordal type of support for a sweatband which also provides an anchor for the lower edges of the cradle whereby to space the latter from the shell and provide a flexible and/or resilient support for the same.

35 Other objects and advantages reside in the particular structure of my device, combination and arrangement of the several parts thereof, and/or in the particular method of utilization of such parts, all of which will be readily apparent to those skilled in the art upon reference to the attached drawing in connection with the following specification wherein the invention is shown, described and claimed.

40 45 In the drawing:

Figure 1 is a bottom plan view of a protective helmet incorporating the invention and showing one manner of utilizing the same;

45 50 Figures 2, 3 and 4 are enlarged fragmentary horizontal sectional views showing alternative ways of anchoring the cradle;

Figure 5 is an enlarged horizontal sectional view showing another method of utilizing the invention;

55 Figures 6 and 7 are views like Figure 5 but showing further methods of using the invention;

Figure 8 is a perspective view of a modified form of cradle strap, parts being broken away; and

Figure 9 is an enlarged fragmentary perspective view of a sweatband according to the invention, parts being cut away and shown in transverse, vertical section.

Referring specifically to the drawing, wherein like reference characters have been used throughout the several views to designate like parts, and referring at first to Figure 1, 10 designates generally any suitable helmet having a crown portion or shell 11 and a brim portion 12.

To space the shell 11 from the head of the wearer, there has been provided a helmet suspension such as the sweatband 13 and a cradle generally indicated at 14. It is to be understood that the helmet suspension may be of any suitable form, whereby the structures shown and described are illustrative only. With this in view, the sweatband 13, see Figure 9, may comprise a body 15 of any suitable cushioning or absorbent material such as felt or sponge rubber. The inner surface of the body 15 is covered with a strip 16 of any suitable material, such as leather, plastic or the like which also may overlie the upper edge of the body 15, as at 17, and the upper portion of the outer surface of the body 15, as at 18. The outer surface of the body 15 may be covered by a strip 19 of any suitable material, the lower edge of which may be secured to the body 15 in any suitable manner as by the stitching 20. The upper edge of strip 19 may underlie the down-turned edge 18 of strip 16 and be secured thereto and to the body 15 as by the stitching 21. Preferably, the outer covering strip 19 is formed with a plurality of pairs of horizontally aligned lacing eyes 22 which may be lined with eyelets 23. The purpose of the eyes 22 will be apparent hereinafter.

By way of example, the cradle 14, illustrated in Figures 1-5 and 7 or the cradle 14' of Figure 6, comprises a plurality of substantially identical cradle straps 24, the upper ends of which are formed to provide tunnels 25 for a flexible loop 26 whereby the upper ends of the straps are connected together. The lower ends of the straps 24 are each formed with a pair of horizontally aligned lacing eyes 27 or other equivalent attaching means, the purpose of which will be apparent hereinafter.

Figure 8 illustrates a modified form of cradle strap wherein a strap 24' is doubled on itself to form a tunnel 25' at the doubled end. The lower ends of the strap 24' may be hemmed as at 28 and connected together by eyelets 29 providing lacing eyes 27'. Obviously other forms of cradle and/or cradle straps may be utilized.

To support the sweatband 13 and cradles 14 and 14', there has been provided an elongated flexible member 30 which is connected to the shell 11 of the helmet 10 in any suitable manner so as to provide an endless series of chords or chordal portions 31 around the interior of the shell 11. The member 30 may be a band or a lace. In the form illustrated the member 30 is a lace and is connected to the shell 11 by being laced through a plurality of pairs of lacing eyes 32 formed therethrough or other equivalent connecting means. It should be noted that the pairs of lacing eyes are not necessarily uniformly spaced from each other whereby some chords 31 may be longer than others. Obviously, such spacing could be uniform if desired.

While it would be possible to accomplish one

purpose of the invention by mounting the flexible member 30 so as to achieve the end-to-end chord arrangement of the Scholl et al. and Ridgell patents, *supra*, I prefer to anchor the flexible member with a series of loops having crossing ends wherein the bights 33 thereof are anchored to the shell 11 and the crossing ends form the chords 31. Thus, the ends of each chord 31 overlap the adjacent ends of both adjacent chords 31 to provide continuous working portions of the member 30 which are spaced from the shell 11. Such working portions comprise the portions of each chord 31 which are between the intersections with adjacent chords. Moreover, it is preferred that alternate chords 31 lie wholly above intermediate chords so that upward flexing of such alternate chords will not be impeded by engagement with such intermediate chords. Conversely, this arrangement serves to retard upward flexing of such intermediate chords.

The foregoing structure permits the flexible member 30 to be connected to the sweatband 13 and to the lower edges of the cradle 14 in a variety of ways to achieve different degrees of resiliency or flexibility in the support. Some of such ways are illustrated in the drawing.

In Figure 1, for instance, the lower ends of the cradle straps 24 are laced to certain chords 31 which are also laced to the sweatband 13, which may be laced at additional points to the member 30 as well.

Figure 5 shows an arrangement wherein the straps 24 are laced to chords 31 which lie between chords 31 which are laced to the sweatband 13. Figure 6 is to the same effect although there the number of cradle straps 24 is such that every alternate chord supports a cradle strap while every intermediate chord is connected to the sweatband. In all arrangements where the cradle is connected to a plurality of chords the upward flexing of the cradle can be enhanced by connecting the same to chords which lie wholly above adjacent chords (Fig. 5); retarded by connecting the cradle to chords lying wholly below adjacent chords (Fig. 6); or a mixed effect can be achieved as in Figure 1, whereby the rearmost supporting chords 31 are freely upwardly flexible while upward flexibility of the foremost supporting chord is retarded. Further modifications of the arrangement are obvious.

It should be noted also that the laced connection illustrated in Figures 1, 5 and 6 is a sliding connection whereby full advantage of the flexible support may be taken without binding or buckling of the straps or sweatband.

Figures 2, 3 and 4 illustrate three additional ways of connecting the cradle 14 to the shell 11. Thus, in Figure 2, a cradle strap 24 is relatively tightly connected to the shell 11 by being laced to the bights 33 of two adjacent loops of alternate chords 31. A slightly looser or medium tight connection is achieved in Figure 3 where the strap 24 is connected to one bight 33 and to an adjacent chord. A still looser or medium loose connection occurs in Figure 4 where the strap 24 is laced to two adjacent chords. The most flexible or resilient connection occurs, of course, where each strap 24 is connected to a single chord 31 as in Figures 1, 5 and 6.

However, the connection between the cradle 14 and the shell 11 may be of different degrees of tightness or resiliency at different points around the shell. For example, in Figure 7, one of the cradle straps 24 is loosely connected

to the shell 11 in the manner shown in Figures 1, 5 and 6 while the remaining cradle straps 24 are connected to the shell 11 in the medium tight manner disclosed by Figure 3. Obviously, further variations utilizing these connections, the tight connection of Figure 2 or the medium loose connection of Figure 4, will occur to those skilled in the art whereby it is thought to be unnecessary to specifically describe them or illustrate them in the drawing.

It is to be noted that it is unnecessary to connect the sweatband 13 or cradle 14 to every chord 31 of the flexible member 30. For instance in Figures 1, 5 and 7, certain chords 31' are not connected to either sweatband or cradle. Nevertheless, such chords 31' are located to engage the sweatband 13 with a shock absorbing engagement when the necessity arises. However, it is contemplated that the sweatband 13 will be provided with a sufficient number of pairs of lacing eyes 22 or other connecting means which are so located as to permit the attachment of the sweatband to any or every chord 31 or 31' if desired. In like manner, any usable number of cradle straps 24 may be provided or even a cradle wherein the lower ends of the straps are joined together by a band (not shown) in which any desired number of pairs of lacing eyes 27 are formed, whereby the cradle also could be connected to any or all of the chords.

Obviously, the device of the invention is capable of great flexibility in use to meet specific needs. Moreover, further variations in tightness or resiliency may be achieved by tightening or loosening the flexible member 30 which may be a lace with the ends tied together. Likewise, where the member 26, which connects the upper ends of the cradle straps 24, is a lace, adjustment of such straps is possible by loosening or tightening such lace. Different head sizes may readily be obtained merely by utilizing a plurality of differently sized sweatbands 13 or by utilizing a single-size band which is adjustable as to size in any of a number of well known ways.

Thus, while I have shown and described what is now thought to be the preferred embodiments of the invention, it is to be understood that the same is susceptible of other forms and expressions. Consequently, I do not limit myself to the precise structures and arrangements shown and described hereinabove except as hereinafter claimed.

I claim:

1. In a protective helmet shell having an arcuate interior, the combination with a sweatband and a cradle comprising a plurality of cradle straps having free lower ends; of an elongated flexible member extending about the interior of said shell, means connecting spaced portions of said member to said shell to provide an endless series of chordal portions spanning arcuate portions of said shell interior, said chordal portions having opposite end portions crossing adjacent end portions of adjacent chordal portions to provide medial areas of said chordal portions lying between said crossed end portions, means connecting medial areas of certain spaced chordal portions to said sweatband, and means connecting said free ends of said cradle straps to medial areas of certain other spaced chordal portions said last named spaced chordal portions being located intermediate those to which said sweatband is connected.

2. In a protective helmet shell having an arcuate interior, the combination with a sweatband

5 and a cradle comprising a plurality of cradle straps having free lower ends; of an elongated lace for adjustably connecting said sweatband and said free ends of said cradle straps to said shell, said shell being formed with a series of lacing eyes therearound, said lace being laced through said eyes to provide an endless series of chordal portions around the interior of said helmet, said lace being so laced through said lacing eyes that the ends of each chordal portion cross the adjacent ends of two adjacent chordal portions, said sweatband and said free ends of said cradle straps being formed with lacing eyes, certain spaced chordal portions of said lace being laced through lacing eyes of said sweatband, and at least some intermediate spaced chordal portions of said lace being laced through said lacing eyes of said free ends of said cradle straps.

3. In a protective helmet shell having an arcuate interior, the combination with a sweatband and a cradle comprising a plurality of cradle straps having free lower ends; of an elongated flexible member extending about the interior of said shell, means connecting spaced portions of said member to said shell to provide an endless series of chordal portions spanning arcuate portions of said shell interior, said flexible member being so connected to said shell that the ends of each chordal portion cross the ends of the two adjacent chordal portions, alternate chordal portions being connected to said sweatband, and the intermediate chordal portions being connected to said free ends of said cradle straps so as to support the latter in inwardly spaced relation to said shell.

4. In a protective helmet shell having an arcuate interior, the combination with a sweatband and a cradle comprising a plurality of cradle straps having free lower ends; of an elongated lace for adjustably connecting said sweatband and said free ends of said cradle straps to said shell, said shell being formed with a series of lacing eyes therearound, said lace being laced through said eyes to provide a plurality of spaced loops, each loop including a bight which encircles a portion of said shell between adjacent lacing eyes in the latter whereby the ends of each bight cross to provide an endless series of overlapped chordal portions about the interior of said shell, said sweatband and said free ends of said cradle straps being formed with lacing eyes, certain spaced chordal portions of said lace being laced through said lacing eyes of said sweatband, and at least some intermediate spaced chordal portions of said lace being laced through said lacing eyes of said free ends of said cradle straps.

5. In a protective helmet shell having an arcuate interior, the combination with a sweatband and a cradle comprising a plurality of cradle straps having free lower ends; of an elongated lace for adjustably connecting said sweatband and said free ends of said cradle straps to said shell, said shell being formed with a series of lacing eyes therearound, said lace being laced through said eyes to provide a plurality of spaced loops, each loop including a bight which encircles a portion of said shell between adjacent lacing eyes whereby the ends of each bight cross to provide an endless series of overlapped chordal portions about the interior of said shell, said sweatband and said free ends of said cradle straps being formed with lacing eyes, certain spaced chordal portions of said lace being laced through lacing eyes of said sweatband, and at least some certain spaced chordal portions being also

laced through said lacing eyes of said cradle straps to connect said cradle and sweatband to said shell in spaced relation to the interior thereof.

6. The structure of claim 5, and said certain spaced chordal portions which are connected both to said sweatband and to said cradle straps being located to cross the adjacent end portions of adjacent chordal portions above the planes of such adjacent chordal portions to permit free upward flexing of the cradle and sweatband supporting chordal portions.

7. In a protective helmet shell having an arcuate interior, the combination with a cradle comprising a plurality of cradle straps having free lower ends; of an elongated flexible member extending about the interior of said shell, spaced portions of said member being connected to said shell to provide an endless series of chordal portions spanning arcuate portions of the shell interior, said flexible member being so connected to said shell that the ends of each chordal portion cross the ends of the two adjacent chordal portions, and said free ends of said straps being connected to chordal portions of said flexible member intermediate the crossed ends of such chordal portions whereby to connect said cradle to said shell in spaced relation thereto.

8. In a protective helmet shell having an arcuate interior, the combination with a flexible cradle having free lower edge portions; of an elongated flexible member extending about the interior of said shell, spaced portions of said member being connected to said shell to provide an endless series of chordal portions spanning arcuate portions of the shell interior, said flexible member being so connected to said shell that the ends of each chordal portion cross shell that of the two adjacent chordal portions, and said lower edge portions of said cradle being connected to chordal portions of said flexible member intermediate the crossed ends of such chordal portions whereby to connect said cradle to said shell in spaced relation thereto.

9. In a protective helmet shell having an arcuate interior, the combination with a cradle including a plurality of cradle straps having free lower ends; of an elongated lace for adjustably connecting said cradle to said shell, said shell being formed with a series of lacing eyes therearound, said lace being laced through said eyes to provide a series of spaced loops, each loop including a bight which encircles a portion of said shell between adjacent lacing eyes, whereby the ends of each bight cross to provide an endless series of overlapped chordal portions about the interior of said shell, said free ends of said cradle straps each being formed with a pair of laterally spaced lace-engaging portions, and at least one cradle strap being laced to a pair of adjacent chordal portions whereby to connect said cradle straps to said shell in spaced relation thereto.

10. In a protective helmet shell having an arcuate interior, the combination with a cradle including a plurality of cradle straps having free lower ends; of an elongated lace for adjustably connecting said cradle to said shell, said shell being formed with a series of lacing eyes therearound, said lace being laced through said eyes to provide a series of spaced loops, each loop including a bight which encircles a portion of said shell between adjacent lacing eyes, whereby the ends of each bight cross to provide an endless series of overlapped chordal portions about the interior of said shell, said free ends of said cradle

straps each being formed with a pair of laterally spaced lace-engaging portions, and at least one cradle strap being laced by one lace engaging means to a bight of one of said loops and by the other lace engaging means to a chordal portion adjacent such bight.

11. In a protective helmet shell having an arcuate interior, the combination with a cradle including a plurality of cradle straps having free lower ends; of an elongated lace for adjustably connecting said cradle to said shell, said shell being formed with a series of lacing eyes therearound, said lace being laced through said eyes to provide a series of spaced loops, each loop including a bight which encircles a portion of said shell between adjacent lacing eyes, whereby the ends of each bight cross to provide an endless series of overlapped chordal portions about the interior of said shell, said free ends of said cradle straps each being formed with a pair of laterally spaced lace-engaging portions, and at least one cradle strap being laced by one lace engaging means to a bight of one of said loops and by the other lace engaging means to a bight of an adjacent loop whereby to connect said cradle straps substantially tightly to said shell.

12. In a protective helmet shell having an arcuate interior, the combination with a sweatband and a cradle comprising a plurality of cradle straps having free lower ends; of an elongated flexible member extending about the interior of said shell, means connecting spaced portions of said member to said shell to provide an endless series of chordal portions spanning arcuate portions of said shell interior, means connecting spaced chordal portions to said sweatband to connect the same to said shell in inwardly spaced relation to the interior thereof, the remaining chordal portions of said flexible member being unconnected to said sweatband but being positioned to bear at times against the exterior of said sweatband to supplement the action of said first mentioned chordal portions, and means connecting said flexible member to said free lower ends of said cradle straps.

13. In a protective helmet shell having an arcuate interior, the combination with a sweatband and a cradle comprising a plurality of cradle straps having free lower ends; of an elongated flexible member extending about the interior of said shell, means connecting spaced portions of said member to said shell to provide an endless series of chordal portions spanning arcuate portions of said shell interior, means connecting spaced chordal portions to said sweatband to connect the same to said shell in inwardly spaced relation to the interior thereof, the remaining chordal portions of said flexible member being unconnected to said sweatband but being positioned to bear at times against the exterior of said sweatband to supplement the action of said first mentioned chordal portions, and means connecting spaced chordal portions of said flexible member to said free lower ends of said cradle straps, whereby to connect said cradle to said shell in spaced relation to the interior thereof.

14. In a protective helmet having an arcuate interior, the combination with a sweatband and a cradle for supporting a head in inwardly spaced relation to said helmet; of an elongated flexible member extending about the interior of said helmet for connecting said sweatband and said cradle to said helmet, means connecting spaced portions of said flexible member to said helmet to provide an endless series of chordal portions

spanning arcuate portions of said helmet interior, and said flexible member being so connected to said helmet that the ends of each chordal portion cross the adjacent ends of the two adjacent chordal portions to provide an endless series of medial areas of said chordal portions extending entirely around the interior of said helmet in radially inwardly spaced relation thereto, and means connecting at least some of said medial areas to said sweatband and cradle.

15. The structure of claim 14, in which said helmet is formed with a series of lacing eyes therearound to provide said means connecting said flexible member to said helmet, and wherein said flexible member comprises a lace laced through said lacing eyes.

16. In a protective helmet having an arcuate interior, said helmet being formed with a series of spaced lacing eyes therearound, an elongated lace, said lace being laced through said eyes to provide a plurality of spaced bights, each bight encircling a helmet portion between a pair of adjacent eyes and having crossing ends inwardly of said helmet to provide an endless series of overlapping chordal portions about the interior of said helmet, and said chordal portions providing means for supporting a sweatband and a cradle in inwardly spaced relation to said helmet.

17. In a protective helmet having an arcuate interior, an elongated flexible member, means connecting spaced portions of said flexible member to said helmet to provide an endless series of chordal portions spanning arcuate portions of said helmet interior, and each chordal portion being disposed in overlapping relation to the two adjacent chordal portions to provide an endless series of medial areas of said chordal portions extending entirely around the interior of said helmet in radially inwardly spaced relation thereto, and said medial areas comprising means for supporting a sweatband and a cradle in said helmet.

18. In a protective helmet having an arcuate interior, the combination with a sweatband for supporting a head in inwardly spaced relation to said helmet; of an elongated flexible member extending about the interior of said helmet for connecting said sweatband to said helmet, means connecting spaced portions of said flexible member to said helmet to provide an endless series of chordal portions spanning arcuate portions of said helmet interior, said flexible member being so connected to said helmet that the ends of each chordal portion cross the adjacent ends of the two adjacent chordal portions to provide an endless series of medial areas of said chordal portions extending entirely around the interior of said helmet in radially inwardly spaced relation thereto, and means connecting at least some of said medial areas to said sweatband to connect the latter to said helmet in inwardly spaced relation thereto.

19. The structure of claim 18, in which said helmet is formed with a series of lacing eyes therearound to provide said means connecting said flexible member to said helmet, and wherein said flexible member comprises a lace laced through said lacing eyes.

20. In a protective helmet having an arcuate interior, the combination with a cradle for supporting a head in inwardly spaced relation to said helmet; of an elongated flexible member extending about the interior of said helmet for

connecting said cradle to said helmet, means connecting spaced portions of said flexible member to said helmet to provide an endless series of chordal portions spanning arcuate portions of said helmet interior, said flexible member being so connected to said helmet that the ends of each chordal portion cross the adjacent ends of the two adjacent chordal portions to provide an endless series of medial areas of said chordal portions extending entirely around the interior of said helmet in radially inwardly spaced relation thereto, and means connecting at least some of said medial areas to said cradle to connect the latter to said helmet in inwardly spaced relation thereto.

21. The structure of claim 20, in which said helmet is formed with a series of lacing eyes therearound to provide said means connecting said flexible member to said helmet, and wherein said flexible member comprises a lace laced through said lacing eyes.

22. In a protective helmet having an arcuate interior, an elongated flexible member, means connecting spaced portions of said flexible member to said helmet to provide an endless series of chordal portions spanning arcuate portions of said helmet interior, and each of said chordal portions crossing at least two adjacent chordal portions, whereby to provide an endless series of chordal portion medial areas extending entirely around said helmet interior in radially inwardly spaced relation thereto, said chordal portions providing means for supporting a helmet suspension in said helmet in inwardly spaced relation thereto.

23. In a protective helmet having an arcuate interior, said helmet being formed with a series of spaced lacing eyes therearound, an elongated lace laced through said eyes to provide an endless series of chordal portions spanning arcuate portions of said helmet interior, and each of said chordal portions crossing at least two adjacent chordal portions, whereby to provide an endless series of chordal portion medial areas extending entirely around said helmet interior in radially inwardly spaced relation thereto, said chordal portions providing means for supporting a helmet suspension in said helmet in inwardly spaced relation thereto.

24. In a protective helmet having an arcuate interior, flexible suspension means therefor, said means comprising flexible means spanning arcuate portions of said helmet interior to provide an endless series of chordal portions, and each chordal portion crossing at least two adjacent chordal portions to provide an endless series of medial areas of said chordal portions extending entirely around said helmet interior in radially inwardly spaced relation thereto, said chordal portions providing means for supporting a helmet suspension in said helmet in inwardly spaced relation thereto.
